UNITED STATES PATENT OFFICE.

LESTER THAYER, OF WINTHROP, MASSACHUSETTS, ASSIGNOR TO FORBES LITHOGRAPH MANUFACTURING COMPANY, OF BOSTON, MASSACHUSETTS, A CORPORATION OF MASSACHUSETTS.

METHOD OF AND APPARATUS FOR LITHOGRAPHING.

Application filed July 18, 1923, Serial No. 652,335. Renewed January 16, 1926.

To all whom it may concern:

Be it known that I, LESTER THAYER, a citizen of the United States, and a resident of Winthrop, county of Suffolk, State of Massachusetts, have invented an Improvement in a Method of and Apparatus for Lithographing, of which the following description, in connection with the accompanying drawings, is a specification, like characters on the drawings representing like parts.

This application is a continuation in part of my prior application Serial No. 565,215, filed June 1, 1922.

My invention relates to a method of and apparatus for lithographing and particularly but not exclusively to a method of and apparatus for making lithographed cartons.

According to prior methods of making cartons the carton blanks are lithographed or otherwise printed in multiple on sheets of relatively large size, and after removal from the press are divided into smaller sheets and subsequently removed to a cutting and scoring machine for finishing the blanks preparatory to fabrication of the completed cartons.

In the cutting and scoring machine the edges of the blanks are used as gage lines properly to position the blanks with relation to the cutting and scoring rules, and I have found that owing to the unavoidable expansion and contraction of the sheets it is impossible by prior methods economically to handle a large number of sheets and obtain a product in which the blanks are uniformly cut and scored in proper relation to the lithographed or printed matter thereon. The sheets, it will be understood, absorb moisture from the atmosphere. If the sheets, for example, are stacked upon discharge from the lithographing press awaiting removal to the machine for dividing them into smaller sheets, evaporation and absorption of moisture will be different for different sheets, causing the sheets to be of slightly different size, with the result that the edges of the sheets after division will not be uniformly and properly spaced relative to the lithographed matter, this causing improper scoring and cutting of the blanks in the cutting and scoring machine, with the result that a considerable number of blanks will be spoiled.

According to my improved process I split the sheets simultaneously with the lithographing and use the split edges of the smaller sheets as gage lines in the cutting and scoring machine, and am thereby enabled to avoid the effects due to expansion and contraction of the sheets, as pointed out above.

My invention will be best understood from the following description showing by way of example one manner of carrying out my method and describing one example of a press for splitting the sheets simultaneously with the lithographing.

In the drawings Fig. 1 shows more or less diagrammatically my invention applied to a flat bed press;

Fig. 2 shows a press constructed according to Fig. 1 looking from the left with the bed in section;

Fig. 3 shows a detail of the impression cylinder for the machine constructed according to Fig. 1; and

Fig. 4 is a perspective view of a fragment of the knife.

Referring to the drawings which illustrate the preferred form of my invention when applied to a flat bed press I have indicated a bed 1 which is mounted for reciprocation on the track 3, while above the bed I have shown the impression cylinder 5, which as will be understood by those skilled in the art is caused to rotate when the bed reciprocates. I have indicated the feeding mechanism for the sheets diagrammatically at 7 and the delivery mechanism for the sheets diagrammatically at 9, the sheets as is common in this type of machine being fed by the impression cylinder in the direction of the arrow 11 whence they pass between the impression cylinder and bed and are finally delivered in the direction of the arrow 13 to the delivery mechanism 9. As will be understood when the sheet passes between the bed and the impression cylinder the sheet is lithographed.

Referring to Fig. 2 I have indicated at 15 the plates which supply the color to the sheet, said plates being supported on the usual blocks 17. On the bed I further mount a knife 19 (or if desired several knives arranged parallel to each other) supported between the blocks 17, which knife (or

knives) as illustrated in Fig. 4 is in the form of a bar or narrow strip of metal having the splitting edge 21.

Cooperating with the knife and serving as a platen therefor is the band 23 preferably constructed of a flexible strip of steel which encircles the impression cylinder. About that portion of the impression cylinder which faces the plates during the printing operation I provide the packing 25, the band in the manner hereinafter explained being caused to have its outer surface substantially flush with the outer surface of the packing.

As shown the impression cylinder is provided with the longitudinally extending recesses 27, and for holding the band 23 in position the ends thereof are bent over and if necessary secured to blocks 29 located at one of these recesses, the band and the blocks being perforated to receive the oppositely screw threaded ends of the turnbuckle 31, the perforations 33 of the blocks being screw threaded to receive the turnbuckle, and the turnbuckle intermediate its ends being provided with the nut 35 whereby the turnbuckle may be operated.

For adjusting the band 23 radially of the impression cylinder to bring the outer surface of the band in proper relation with the knife to compensate for the wear on the cutting edge of the knife and to bring the outer surface of the band substantially flush with the outer surface of the packing I insert shims 37 between the impression cylinder and the band, the turnbuckle permitting the band to be loosened and adjusted for this purpose. The shims may be of any suitable material and preferably material which will more or less yieldingly support the band, and for this purpose I have found shims made of several layers of paper satisfactory.

In using the press construction as described the sheets preferably are fed to the impression cylinder in such manner that the knife splits the sheets into narrower sheets on a line transversely to the grain of the sheets. As the sheets are split simultaneously with the lithographing the lithographs are always in the same relation to the edge along which the split takes place. As the maximum expansion or contraction of the sheets is along the grain splitting the sheets transversely of the grain minimizes or insures against any noticeable effects due to subsequent expansion or contraction. The sheets are now removed to the cutting and scoring machine, the split edges of the sheets being placed against the "front" guides of the feeding mechanism of the cutting and scoring machine and the unsplit edges against the "side" guides thereof which because the lithographed portions of the sheets are in exact relation to the split edges permits the sheets to be cut and scored accurately with relation to the lithographs. As will be un-

derstood by those skilled in the art the scoring rules in the cutting and scoring machine for the most part and especially the longest rules will be arranged parallel to the "front" guides of the cutting and scoring machine, and in this manner the scoring will be accurately placed relatively to the split edge of the sheet and will cause the sheets to be scored across the grain which permits the sheets to be folded without buckling at the edges of the cartons.

The presses in which cartons are printed are commonly called lithographing presses and the cartons said to be "lithographed" whether the cartons are printed in colors or not or whether they bear both type matter, and pictorial matter or either of these alone. Accordingly it is to be understood that I do not limit myself to the particular kind of printing done by the press.

Although I have described one form of press for simultaneously lithographing and splitting the sheets it will be understood that other forms may be employed, as for example those disclosed in my pending applications Serial No. 565,215, filed June 1, 1922 and Serial No. 652,336, filed July 18, 1923.

Although I have described for purposes of illustration one embodiment of my apparatus and method it is to be understood that I am not limited thereby, but that within the scope of my invention wide deviations may be made therefrom without departing from the spirit of my invention.

Claims:—

1. The method of making lithographed cartons or the like which comprises printing said cartons in multiple on sheets of relatively large size, simultaneously splitting said sheets into sheets of smaller size, and subsequently using the split edges of the smaller sheets as a gauge in a cutting and scoring machine for the cartons.

2. The method of making lithographed cartons or the like which comprises printing and said cartons in multiple on sheets of relatively large size, simultaneously splitting said sheets transversely to the grain into sheets of smaller size, and subsequently using the split edges of the smaller sheets as a gauge in a cutting and scoring machine for the cartons.

3. That method of making lithographed cartons in which a lithographing press and a cutting and scoring machine are used, the latter having front and side guides, which comprises printing in said lithographing press said cartons in multiple on sheets of relatively large size, simultaneously splitting said sheets transversely to the grain into sheets of smaller size to prepare them for said cutting and scoring machine, and using said split edges as a gauge engaging the front feed guides of said splitting and scoring machine.

4. A flat bed carton lithographing press having a rotary impression member and a bed carrying plates for printing said cartons in multiple, a knife arranged lengthwise of said bed and set up among said plates whereby said knife will split the sheet into smaller sheets each having a plurality of duplicate lithographs for said cartons, a band encircling said impression member, tension means for said band, shims for adjusting said band radially of said impression member, packing for said impression member, and the outer face of said band being substantially flush with the outer face of said packing and serving as a platen for said knife.
5. In a flat bed press, a rotary impression cylinder, a straight knife arranged lengthwise of said bed and set up among the plates on said bed, and a radially adjustable band encircling said impression cylinder intermediate its length and serving as a platen for said knife.
6. In a flat bed press, a rotary impression cylinder, a straight knife arranged lengthwise of said bed and set up among the plates on said bed, a radially adjustable platen for said knife carried by said impression cylinder, and packing carried by said impression cylinder at each side of said platen.
7. In a flat bed press, a rotary impression cylinder, a knife set up lengthwise of said bed and among the plates on said bed, a platen for said knife carried by said impression cylinder, and packing carried by said impression cylinder at each side of said platen.
8. In a flat bed press, a rotary impression cylinder, a knife set up lengthwise of said bed and among the plates on said bed, a flexible band serving as a platen for said knife bent about said impression cylinder intermediate its length, and means for securing the end portions of said band to said cylinder.
9. In a press, an impression cylinder, a band encircling said cylinder, a tension de-
- vice for said band mounted in a recess on said cylinder, and a reciprocatory plate carrying bed cooperating with said impression cylinder, a knife carried by said bed transversely to the axis of said impression cylinder, and a plurality of plates set up on said bed on each side of said knife.
10. In a flat bed press, a reciprocatory plate carrying member, an impression member, a knife set up among the plates on said plate carrying member transversely to said impression member, a narrow band serving as a platen for said knife carried by said impression member intermediate its length, and shims for adjusting said band radially of said impression member.
11. In a flat bed press, a reciprocatory plate carrying member, an impression member, a knife set up among the plates on said plate carrying member transversely to said impression member, a narrow band serving as a platen for said knife carried by said impression member intermediate its length, and shims of yielding material for adjusting said band radially of said impression member.
12. In a flat bed press, a reciprocatory plate carrying member, an impression member, a knife set up among the plates on said plate carrying member transversely to said impression member, a narrow band serving as a platen for said knife carried by said impression member intermediate its length, and a yielding backing for said band.
13. In a flat bed press, a reciprocatory plate carrying member, an impression member, a knife set up among the plates on said plate carrying member transversely to said impression member, a narrow band serving as a platen for said knife carried by said impression member intermediate its length, means for tensioning said band, and means for adjusting said band radially of said impression member.

In testimony whereof, I have signed my name to this specification.

LESTER THAYER.

Certificate of Correction.

It is hereby certified that in Letters Patent No. 1,579,181, granted March 30, 1926, upon the application of Lester Thayer, of Winthrop, Massachusetts, for an improvement in "Methods of and Apparatus for Lithographing," an error appears in the printed specification requiring correction as follows: Page 2, line 111, claim 2, strike out the word "and"; and that the said Letters Patent should be read with this correction therein that the same may conform to the record of the case in the Patent Office.

Signed and sealed this 11th day of May, A. D. 1926.

[SEAL.]

M. J. MOORE,
Acting Commissioner of Patents.
